US0D1019595S

(12) **United States Design Patent** (10) **Patent No.:** **US D1,019,595 S**
(45) **Date of Patent:** **** Mar. 26, 2024**

(54) **SPEAKER**

- (71) Applicant: **Guangzhou Rantion Technology Co., Ltd.**, Guangdong (CN)
(72) Inventor: **Yongning Huang**, Guangdong (CN)
(73) Assignee: **Guangzhou Rantion Technology Co., Ltd.**, Guangzhou (CN)

(**) Term: **15 Years**

(21) Appl. No.: **29/915,195**

(22) Filed: **Oct. 26, 2023**

Related U.S. Application Data

- (62) Division of application No. 35/515,784, filed on Nov. 21, 2022 (U.S. filing date under 35 U.S.C. 384), and having an international filing date of Nov. 21, 2022.

(57) **CLAIM**

The ornamental design for a speaker, as shown and described.

DESCRIPTION

FIG. 1 is a front, top perspective view of a speaker, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of detail "9" identified in FIG.1. The dashed lines in the figures illustrate portions of the speaker that form no part of the claimed design. The dash dot dash lines in FIGS. 1 and 9 are for the purpose of illustrating the enlarged view indicators and form no part of the claimed design.

1 Claim, 9 Drawing Sheets
